UNITED STATES PATENT OFFICE.

HERMAN J. SCHOEN, OF BROOKLYN, NEW YORK.

ATTACHMENT FOR PRINTING-PRESSES.

No. 833,553.

Specification of Letters Patent.

Patented Oct. 16, 1906.

Application filed April 24, 1906. Serial No. 313,368.

To all whom it may concern:

Be it known that I, HERMAN J. SCHOEN, a citizen of the United States, and a resident of Brooklyn, in the county of Kings and State 5 of New York, have invented certain new and useful Improvements in Attachments for Printing-Presses, of which the following is a specification.

My invention relates to attachments for 10 printing-presses.

It has for its object to provide an attachment for printing-presses embodying means for adjustably supporting a platen thereon, whereby it may be advanced or retracted to 15 the proper position required to obtain a perfect impression from a plate.

It has for a further object to provide an attachment of the character described, which is simple and inexpensive in construction, easily 20 operated, and which will be perfectly rigid in its adjusted position.

In the drawings, Figure 1 is a plan view 25 of my attachment; Fig. 2, a transverse sectional view; Fig. 3, a longitudinal sectional view, the platen being removed; Fig. 4, a bottom plan view of the platen, and Fig. 5 a perspective view of one of the blocks for advancing or retracting the platen.

Like reference characters designate corre- 30 sponding parts in all the figures of the drawings illustrating my invention.

Referring to the drawings, 1 designates the 35 box or base, which, as usual in all plate-printing presses, is adapted to be reciprocally sup- ported on the press so as to allow it to be brought into and out of contact with the plate being printed from.

Blocks 2 and 3 are secured side by side 40 within the box by means of longitudinal dove- tail projections 4 and 5, respectively, on their under faces slidably engaging longitudinal dovetail grooves 5^a and 6^a, respectively, in the bottom of said box, the block 2 being provided with an inclined upper face 6 and a 45 dovetail projection 7 thereon inclined in the same direction as said upper face and the block 3 being provided with an upper face 8, inclined in the opposite direction to the face 6 of the other block and having a dovetail 50 projection 9 thereon inclined in the same di- rection as said upper face, but in the opposite direction to the projection of the other block. A platen 10 is supported within the box upon 55 said blocks and is provided with oppositely- inclined under faces 9^a and 10^a, slidably en- gaged by the faces 6 and 8, respectively, of

said blocks and having oppositely-inclined dovetail grooves 11 and 12, respectively, therein slidably engaged by the projections 7 and 9, respectively, of said blocks.

The meeting edges of the blocks 2 and 3 are undercut and provided with teeth cut therein and forming racks 12^a and 13, respectively engaged by an idler-pinion 14, rotatably journaled on a stub-shaft 15, secured in a 65 hole in the bottom of the box or base 1, whereby the blocks are made to move in opposite directions.

A screw-threaded shaft 16 extends through a screw-threaded hole 17 in one end of the 70 box or base, one end of said shaft being provided with a head 18, rotatably engaging a slot 19 in one end of the block 3 and the other end being squared to provide for the engagement of a wrench for turning it.

It will be appreciated that the attachment constructed in the manner above described will be easily and readily adjustable and form a solid support for the platen, thereby rendering it possible to take a perfect im- 80 pression from a plate being printed from.

The operation is as follows: It being assumed that the blocks are in the position shown by Figs. 1 to 3, inclusive, in which position the platen will be in its advanced position, to retract the platen the shaft is turned in the direction to force it inwardly, with the result that the block 3 will be slid to the left, and by reason of the idler-pinion meshing with the racks of the blocks the block 2 will 90 be concurrently slid to the right, and by reason of the inclined upper faces of the blocks riding against the inclined under faces of the platen it will be retracted, and to advance the platen again the shaft is turned in the direc- 95 tion to draw it outwardly, thereby forcing the blocks to move concurrently in the reverse direction to that above described.

I do not wish to limit myself to the precise details and arrangements of parts shown and described, but reserve the right to all modifications within the scope of my invention.

Having now described my invention, what I claim as new, and desire to secure by Letters Patent, is—

1. An attachment for printing-presses embodying a base, blocks laterally disposed reciprocal concurrently thereon side by side in opposite directions, a platen supported on said blocks and means for reciprocating said blocks to advance or retract said platen, substantially as described.

2. An attachment for printing-presses embodying a base, blocks laterally disposed concurrently reciprocal thereon side by side in opposite directions, a platen supported on said blocks, means for slidably securing said blocks on said base and to said platen and means for reciprocating said blocks to advance or retract said platen, substantially as described.
- 10 3. An attachment for printing-presses embodying a base, blocks concurrently reciprocal thereon side by side in opposite directions and having racks, a pinion meshing with said racks a platen supported on said blocks and means for reciprocating said blocks to advance or retract said platen, substantially as described.
- 15 4. An attachment for printing-presses, embodying a box, blocks concurrently reciprocal therein side by side in opposite directions and having racks, a pinion meshing with said racks a platen supported on said blocks and means for reciprocating said blocks to advance or retract said platen, substantially as described.
- 20 5. An attachment for printing-presses embodying a base, blocks concurrently reciprocal thereon side by side in opposite directions and having racks, a pinion meshing with said racks, a platen supported on said blocks, means for slidably securing said blocks on said base and to said platen, and means for reciprocating said blocks to advance or retract said platen, substantially as described.
- 25 6. An attachment for printing-presses embodying a base, blocks reciprocal concurrently thereon side by side in opposite directions and having oppositely-inclined faces, a platen supported on said blocks and having oppositely-inclined faces engaged by the inclined faces of said blocks and means for reciprocating said blocks to advance or retract said platen, substantially as described.
- 30 7. An attachment for printing-presses embodying a base, blocks concurrently reciprocal thereon side by side in opposite directions and having racks, a pinion meshing with said racks, a platen supported on said blocks, means for slidably securing said blocks on said base and to said platen and means for reciprocating said blocks to advance or retract said platen, substantially as described.
- 35 8. An attachment for printing-presses embodying a base, blocks reciprocal concurrently thereon side by side in opposite directions and having oppositely-inclined faces and racks, a pinion meshing with said racks, a platen supported on said blocks and having oppositely-inclined faces engaged by the inclined faces of said blocks, means for reciprocating said blocks to advance or retract said platen, substantially as described.
- 40 9. An attachment for printing-presses embodying a base, blocks concurrently reciprocal thereon side by side in opposite directions, a platen supported on said blocks and a screw engaging one of said blocks for reciprocating said blocks to advance or retract said platen, substantially as described.
- 45 10. An attachment for printing-presses, a base, blocks concurrently reciprocal thereon side by side in opposite directions and having oppositely-inclined faces, a platen supported on said blocks and having oppositely-inclined faces engaged by the inclined faces of said blocks and means engaging one of said blocks for reciprocating both of said blocks to advance or retract said platen, substantially as described.
- 50 11. Signed at New York, in the county of New York and State of New York, this 19th day of April, A. D. 1906.
